UNITED STATES PATENT OFFICE

153,981

DESIGN FOR AN ADJUSTING KNOB

Jean O. Reinecke, Oak Park, Ill., assignor to McGraw Electric Company, Elgin, Ill., a corporation of Delaware

Application July 9, 1946, Serial No. 131,413

Term of patent 14 years

(Cl. D26—1)

To all whom it may concern:

Be it known that I, Jean O. Reinecke, a citizen of the United States, residing in Oak Park, county of Cook, and State of Illinois, have invented a new, original, and ornamental Design for an Adjusting Knob, of which the following is a specification, reference being had to the accompanying drawings, forming a part thereof, in which:

Fig. 1 is a view in front elevation of an adjusting knob showing my new design;

Fig. 2 is a view in side elevation thereof; and
Fig. 3 is a front perspective view thereof.

The design for the adjusting knob disclosed is characterized by the teardrop indicator portion on the end thereof, said indicator portion having a longitudinal extension running along one side of the knob and terminating at the base thereof, as shown.

I claim:

The ornamental design for an adjusting knob, substantially as shown and described.

JEAN O. REINECKE.
